UNITED STATES PATENT OFFICE

KARL SIEG, OF BROOKLAWN, NEW JERSEY, ASSIGNOR TO SAMUEL M. LANGSTON CO.,
A CORPORATION OF NEW JERSEY

PAPER WINDING MACHINE

Application filed May 24, 1930. Serial No. 455,170.

This invention relates to certain improvements in winding machines, and more particularly to that type in which paper from a paper making machine, a reel or other source is slotted into sections or trimmed and re-wound.

The present invention is adapted for use in that type of winding machine which is provided with drums for supporting the paper roll, and a driven pressure roller pressing downwardly upon the surface of the paper roll as it is being wound around the winding shaft. Means are usually provided in this type of winding machine for maintaining the pressure roller in parallelism with the supporting drums, so as to effect a uniform application of pressure from one end of the paper roll to the other. A well-known type of machine which provides for the maintenance of such parallelism involves the use of rack bars which are associated with each end of the pressure roller and which are movable endwise as the roll of material being wound increases in size. These rack bars mesh with gears connected together to rotate simultaneously, said gears thereby serving to insure the simultaneous movement of both ends of the pressure roller and the resultant uniform application of pressure along the length of the roll. In such type of machines, these rack bars extend a material distance above the machine as the roll of material becomes larger in diameter, requiring thereby a corresponding increase in space to accommodate for the extension of these racks. In places where the available vertical space is limited such extensions are a decided disadvantage.

The gears which mesh with the rack bars are positioned towards the top of the machine and connected together to rotate simultaneously with said rack bars. The result is that as soon as the diameter of the roll begins to increase, the end of the rack bar

immediately begins to extend beyond the general contour of the machine.

The present invention accordingly provides means whereby the movable rack bars of a winding machine are more effectively confined within the body of the machine as the roll of material being wound increases in diameter.

In the present invention, the bottom end of each rack bar is disposed close to the base of the machine when the winding shaft is in its lowermost position. The length of these rack bars are made but a little longer than the extreme diameter of the paper roll so that in this lowermost position the top ends of the bar will be a substantial distance below the top of the machine. The gears meshing with these rack bars are positioned just below the tops of the rack bars when in this lowermost position, so that these rack bars will have traveled through nearly their entire range of movement before they begin to extend beyond the general contour of the machine. It is preferred to provide a rack with the teeth facing inwardly towards the main body of the machine and the gear intermeshing therewith correspondingly positioned in order to effect a more compact machine. Through the instrumentality of these improvements, the rack bars of the machine will be confined in a much smaller space during extreme limits of operation.

The invention also consists in certain new and important features of construction and combinations of parts hereinafter set forth and claimed.

Although the novel features which are believed to be characteristic of this invention will be particularly pointed out in the appended claims, the invention itself, as to its objects and advantages, the mode of its operation and the manner of its organization may be better understood by referring to the following description taken in connection

with the accompanying drawings forming a part thereof, in which

Fig. 1 is a front elevation of the machine.

Fig. 2 is a section taken on line 2—2 of Fig. 1.

Like reference characters denote like parts in the several figures of the drawings.

In the following description and in the claims parts will be identified by specific names for convenience, but they are intended to be as generic in their application to similar parts as the art will permit.

In accordance with a specific embodiment of the present invention exemplified in the accompanying drawings, a pair of end frames 10 are provided, supported by base members 11 and 12 and suitably braced together by a plurality of structural elements. The frame pieces 10 serve to support the operating elements of the machine such as the winding shaft, the pressure roller, supporting drums and the like.

The course of the paper to be slotted and wound is indicated by the dot and dash line in Fig. 2, and is shown as passing in contact with the idler rollers 13, 14 and 15, into the field of action of cutters 16 and 17, around the guide roller 18, and in contact with a front supporting or winding drum 20 and then around a rewinding shaft 21. This winding drum 20 co-operates with a similar drum 22, and both conjointly serve to support a roll of paper 23 as well as rotate this roll about the winding shaft 21.

The first idler 13 preferably has its opposite ends supported by vertically adjustable bearings 24 so that the position of this idler may be adjusted to properly engage with the paper in case the latter is loose, or unequally stretched along its transverse width. The idlers 14 and 15 are provided with adjustable friction or brake bands 25 and 26 respectively, whereby the free rotation of these idlers may be selectively resisted to vary the tensions put on the paper.

In order to provide means for driving the winding drums 20 and 22, the shaft 27 of the drum 20 is connected to any suitable source of power and has mounted thereon a gear 28 which serves to drive a similar gear on the shaft 30 of the drum 22 through the intermediary of a gear 31. This intermediate gear 31 also serves to drive a gear 32 mounted on the shaft 33 of the cutters 16 so that said cutters and the winding drums 20 and 22 are driven at the proper relative speeds, and the cutters 17 frictionally driven correspondingly.

The winding shaft 21 which is not positively driven is mounted in bearings 34 carried by bearing blocks 35 adapted to slide vertically along guide bars 36 attached to the front vertical edges of the end frame pieces 10. The two bearing blocks 35 are preferably counter-balanced in any suitable manner (not

shown) so as to effect their independent free flotation without material tendency towards upward or downward movement.

Co-operating with the surface of the roll of material 23 as it is being wound, is a pressure or riding roller 40 mounted on a shaft 41, the ends of which are journaled in vertically movable bearing blocks 42. This pressure roller 40 is positively driven, and for that purpose the shaft 41 thereof has mounted at one end a bevel gear 43 which meshes with a slideable bevel gear 44 keyed on to a vertical shaft 45. The lower end of this shaft 45 carries a bevel gear 46 which meshes with a bevel gear 47 carried on the shaft which carries the intermediate gear 31. By this means, the pressure roller 40 is free to slide vertically as the diameter of the paper roll 23 increases and is continuously rotated in conjunction with this vertical movement.

The gear 47 has a friction drive, and the friction is adjustable, thus the pressure roll can be driven faster than the paper and slip on the surface of the roll, or the friction can slip and the roll will run at the same speed as the paper but exert a pull on the paper.

All of this construction hereinbefore described is old and well-known in the art and forms no part of the present invention. The important feature of this invention resides mainly in the provision of improved means for holding the pressure roller 40 absolutely parallel with the winding drums 20 and 22, so that the constituent elements of this means are more closely confined within the body of the machine when in extreme operating positions. In accordance with this improved means, the bearing blocks 42 may have extending therebetween a bar 50 which carries brackets 51 at each end thereof. These brackets 51 are fixed to a pair of rack bars 52 having the teeth thereof turned rearwardly towards the body of the machine. These rack bars are mounted for slideable movement along the guide bars 53, and are adapted to extend in close proximity to the base of the machine when in the lowest extreme position.

The rack bars 52 mesh with large gears 54 which in turn mesh with small pinions 55 rigidly connected together to a common shaft 56. This shaft 56 is provided with a brake arrangement 57 which can be adjusted to effect selective resistance to the rotation of the gear 54 and consequently to the vertical movement of the roller 40. In this way, the pressure of the roller 40 on the paper roll 23 can be accordingly regulated. The gears 54 are preferably of comparatively large diameter and are preferably positioned approximately midway of the height of the portion of the frame above the drums. The shaft 56 is above and in the rear of the gears 54 so as to be out of the path of the rising roll of paper. Furthermore, the brake 57 be-

ing on a shaft running at higher speed than the rate of linear travel of the rack bars, may be more effectively, easily and accurately adjusted to give the desired resistance to the upward movement of the pressure roll.

5 In the operation of this means for effecting parallelism between the pressure roller 40 and the winding drums 20 and 22, if upward pressure should be exerted on only one 10 end of said pressure roller tending to lift it higher than the other end, this will effect a corresponding upward movement of the co-operating rack bar 52, and effect thereby the rotation of the associated gear 55. This 15 rotation of the gear 55 at one end will cause a corresponding rotation of the gear 55 at the other end, so as to transmit this movement end to its associated rack bar 52. This will cause a simultaneous movement of the 20 bars 52 endwise, and will thereby obviate the possibility of the pressure roller 40 being lifted to a higher level at one end of the roll surface than at the other.

During the initial operation of winding 25 the paper around the winding shaft 21, the lower end of the rack bars 52 will be disposed near the base of the machine proximate the position A indicated in Fig. 2. It should be noted that the length of this rack 30 bar 52 is but slightly longer than the maximum diameter of the paper roll 23. The top of the bars during the initial winding operation will be disposed proximately in the position B. The gears 54 will then be disposed 35 in intermeshed relationship with the rack bars 52 slightly below this position B. When the roll 23 has attained its maximum diameter, the bottom ends of the rack bars 52 will be slightly below the rack meshed portions 40 of the gears 54 while the top ends will be proximately in the indicated position C.

It should be noted that this improved organization permits the gears 54 to be positioned at a substantial distance below the top 45 of the machine, and that the top end of the rack bar will be at a correspondingly lower position when the winding shaft 21 is disposed in its extreme lowermost position. By this means, the top end of the rack bars 52 will have traveled a substantial distance within 50 the body of the machine in response to the increase in diameter of the roll 23 before this end begins to extend beyond the general contour of the machine thereby confining the 55 elements of the machine more closely to the body of the machine during extreme operating positions.

For facilitating the raising of the pressure roller mechanism when the friction brake device 57 is released there is provided a pair of counter-balancing weights 60 vertically slideable on the rear of the end frame 10 and each connected to its corresponding bearing blocks 42 by a chain 61 extending over a pair of 55 sprocket wheels 62 and 63. For positively

raising or lowering the pressure roller mechanism there is provided a crank hand wheel or other suitable means (not shown) operatively connected to one of said sprocket wheels 62 and 63, and adapted to effect said positive 70 movement to said mechanism.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

Having thus described my invention, what 80 I claim as new and desire to secure by Letters Patent is:

1. A winding mechanism including a pressure roller vertically movable in response to the increase in diameter of the web being 85 wound, a rack bar proximate each end of said pressure roller and having means substantially midway between the ends thereof for supporting said roller, and causing the rack 90 bar to move vertically in unison with the associated end of said roller, the bottom ends of said rack bars extending close to the base of the mechanism when in extreme lowermost position, and the length of said rack bars being not materially longer than the maximum 95 diameter of the roll being wound, and means for preventing relative movement between said rack bars.

2. A winding mechanism including a pressure roller vertically movable in response to 100 the increase in diameter of the web being wound, a rack bar proximate each end of said pressure roller and having means substantially midway between the ends thereof for supporting said roller, and causing the rack 105 bar to move vertically in unison with the associated end of said roller, the bottom ends of said rack bars extending close to the base of the mechanism when in extreme lowermost position, and the length of said rack bars being not materially longer than the maximum 110 diameter of the roll being wound, said rack bars having their teeth extending rearwardly towards the body of the mechanism, and means disposed on the side of the mechanism 115 adjacent the teeth of said rack bars for preventing relative movement between said bars.

3. A sheet winder having a main frame, a pressure roller vertically movable thereon, a pair of supporting drums, a pair of rack bars connected to said roller for vertical movement, and means including gears meshing with said rack bars for preventing relative movement between said bars, said gears being disposed approximately midway of the height 125 of the frame above said drums, the rack bars in their lowermost position being below said drums and in their uppermost position being not materially above the top of said frame.

4. A sheet winding machine having a pair 130

- of roll supporting drums, an upper pressure roller, vertically movable rack bars at opposite ends of the machine and connected to said roller for vertical movement therewith, said rack bars having their teeth facing toward the rear of the machine, a pair of separate comparatively large gears meshing with said rack bars, and disposed a substantial distance below the top of the machine, a transverse shaft above and in the rear of said gears and having pinions meshing with said gears, and means for resisting free rotation of said shaft. 5
5. A sheet winding machine having a pair of roll supporting drums, an upper pressure roller, vertically movable rack bars at opposite ends of the machine and connected to said roller for vertical movement therewith, a pair of separate comparatively large gears meshing with said rack bars, a transverse shaft above said gears and having pinions meshing with said gears and means for resisting free rotation of said shaft, and a brake drum on said shaft and of smaller diameter than said gears. 10
- 20 6. A winding machine having a frame, a pair of drums for supporting the roll being wound, a pressure roller resting on the roll and vertically movable as the roll increases in size, means for positively rotating said drums and pressure roller, a pair of vertically slideable bearing blocks on said frame for said pressure roller, a pair of vertically slideable bars provided with rack teeth, said bearing blocks being secured to said bars substantially midway between the upper and lower ends of the latter, and the length of said bars being substantially equal to the maximum diameter of a roll which can be wound on said machine, a pair of gears so positioned on said frame that they mesh with the teeth at the upper ends of the bars when the roll is of minimum diameter, and with the teeth at the lower ends of said bars when said roll is of maximum diameter, said gears being spaced apart axially to permit movement of the upper part of the roll therebetween, a shaft above said gears and having pinions meshing with said gears to insure simultaneous and equal movement of said bars, and means for resisting the free rotation of said shaft. 25
- 30 7. A winding machine including a pair of drums for supporting the roll being wound, a pressure roller vertically movable in response to the increase in the diameter of the roll being wound, a rack bar proximate each end of said pressure roller and adapted to move vertically in unison with the associated end of said roller, and bearing blocks for said roller and secured to said rack bars substantially midway between the ends of the latter. 35
- 40 8. A winding machine including a pressure roller vertically movable in response to the increase in the diameter of the roll being wound, vertically movable rack bars at opposite ends of the machine and connected sub-
- stantially midway between their ends to said roller for vertical movement therewith, said rack bars having their teeth facing towards the rear of the machine, a pair of gears meshing with said racks and spaced apart axially to permit movement of the roll therebetween, said gears being disposed a substantial distance below the top of the machine, and means for preventing relative rotation and resisting any rotation of said gears. 70
